CAR ROOF

Charles David Bonsall, Pittsburgh, Pa., assignor
to P. H. Murphy Company, New Kensington,
Pa., a corporation of Pennsylvania

Application July 3, 1931. Serial No. 548,527

10 Claims. (Cl. 108—5.4)

This invention relates to car roofs and more particularly to car roofs of the type shown in my Patent No. 1,330,975, dated February 17, 1920, wherein the metal roof sheets span the car from side plate to side plate of the car and are rigidly secured together along their adjacent margins by hollow upstanding seams that function as exterior roof supporting carlines.

The principal object of the present invention 10 is to reinforce and strengthen the roof seams and thereby increase the load-carrying capacity of the roof. Other objects are simplicity and cheapness of construction and compactness of design. The invention consists in the parts and 15 arrangements and combinations of parts herein-after described and claimed.

In the accompanying drawing, which forms part of this specification and wherein like symbols refer to like parts wherever they occur,

20 Fig. 1 is a plan view of a portion of the car roof embodying my invention.

Fig. 2 is a vertical cross-section through one-half of the roof on the line 2—2 in Fig. 1.

25 Fig. 3 is a longitudinal cross-section through the roof at the ridge, the section being taken at one of the seams on the line 3—3 in Fig. 2; and

Fig. 4 is a cross-section through the seam adjacent to the eaves on the line 4—4 in Fig. 2.

Referring to the accompanying drawing, my 30 invention is shown in connection with an all-steel riveted-up roof comprising pitched metal roof sheets A extending from side plate B to side plate B of the car and are rigidly connected along their adjacent side margins by hollow upstanding seams C, which function as roof supporting carlines. The side plates B are preferably of substantially Z-shaped cross-section and are arranged with their inner flanges 1 upstanding; and the roof sheets A are provided with depending 35 eaves flanges 2 that overhang and are rigidly secured to the outer faces of said side plate flanges by horizontal rivets 3.

The roof sheets are provided along their adjacent side margins with raised seam flanges 4 that are overlapped to form the hollow upstanding seams C. The side marginal seam flanges gradually diminish in depth from the ridge towards the eaves and gradually change from a substantially inverted L-shaped section 50 at the ridge to a substantially inverted channel-shaped section adjacent to the eaves. At the eaves ends of the roof sheets the side marginal seam flanges 4 thereof are curved downwardly and merge into the plane of the bodies of said 55 sheets where they are turned down to form the depending eaves flanges 2. At points adjacent to the eaves, where the outer walls of the inverted channel-shaped portions of the side marginal seam flanges 4 reach the plane of the roof sheets, said walls are turned outwardly to form

the flanges 5. The overlapped side marginal seam flanges 4 of adjacent roof sheets are rigidly secured together throughout their length preferably by means of rivets 6 that pass through the overlapped top portions thereof.

In order to stiffen and strengthen the whole roof some or all of the upstanding seams or carline portions C thereof are strengthened and stiffened by means of a metal reinforcing members D of substantially Z-shaped cross-section that extend transversely of the car from side plate to side plate alongside of said seams. As shown in the drawing, each of these seam reinforcing members D is preferably arranged outside of the car with its web 7 disposed parallel with one side

75 wall of the seam C, with its bottom flange 8 riveted or otherwise rigidly secured to the body portion of one sheet, and with its top flange 9 overlapping the top of said seam and secured thereto by the rivets 6 that secure together the 80 cooperating seam flanges 4. The Z-shaped seam reinforcing member D is disposed parallel to the longitudinal axis of the seam and is preferably thicker than the sheets and arranged with its web portion 7 spaced from the adjacent side

85 wall of the seam C and thus cooperates with said wall of said seam and the adjacent body portion of the roof sheet to form a hollow box girder. The seam reinforcing member D is of a depth 90 corresponding substantially to the depth of the seam; and likewise said member gradually decreases in depth on opposite sides of the ridge and has downwardly curved end portions that correspond to the downwardly curved eaves end portions of said seam. At the ends of the seam reinforcing member D the upper flange 9 thereof merges into the plane of the lower flange 8 thereof and is bent downwardly to form depending end flanges 10 that overhang the overlapped end 95 portions of the depending eaves flanges 2 of adjacent roof sheets and are rigidly secured to the side plates B by the rivets 3. The seam reinforcing member D is preferably made from a blank of uniform width; and in consequence of the tapering of said member the base flange 8 thereof increases in width from the ridge to the eaves, thereby providing wide bearings at the side plates.

100 By the arrangement described, the Z-shaped seam reinforcing members are rigidly secured to the roof sheets and to the side plates and are adapted by their structure and position to increase the strength and load capacity of the roof; and they also serve to prevent the seam rivets from pulling through the roof sheets, and the sheet flanges from buckling between said rivets. The seam reinforcing members are also especially well adapted to offer resistance to torsional stresses that tend to rack and weave the car body and to the horizontal stresses that tend to throw the car out of square.

What I claim is:

1. A car roof comprising roof sheets secured together along their adjacent margins by raised lap seams, and a reinforcing member extending longitudinally of a seam and having a portion riveted to the top of said seam and a portion riveted to the body portion of that roof sheet which is undermost at said seam. 80
2. A car roof comprising roof sheets rigidly secured together along their adjacent margins by raised lap seams, and a reinforcing member extending longitudinally of a seam with its ends secured to the side members of the car, said member having a flange that overlaps and is riveted to the top of said seam and a flange that is riveted to the body portion of one of the roof sheets at one side of said seam, the portion of the reinforcing member between said flanges being spaced horizontally from the adjacent side wall of said seam. 85
3. A car roof comprising roof sheets rigidly secured together along their adjacent margins by upstanding seams, and a Z-shaped member of greater thickness than the sheets extending longitudinally of a seam with its web extending alongside one side wall of said seam, with its ends secured to the side plates of the car and with one flange overlapping and riveted to the top of said seam and with the other flange riveted to the body portion of one sheet adjacent to said side wall of said seam. 90
4. A car roof comprising roof sheets rigidly secured together along their adjacent margins by upstanding seams, and a Z-shaped member extending longitudinally of a seam with its web extending alongside one side wall of said seam, with one flange overlapping and riveted to the top of said seam by the rivets which secure said seam and with the other flange riveted to the body portion of one sheet adjacent to said side wall of said seam, said web portion decreasing in depth from the middle of said reinforcing member to the ends thereof and said last mentioned flange increasing in width from the middle of said reinforcing member to the ends thereof. 100
5. A car roof comprising roof sheets rigidly secured together along their side margins by hollow upstanding seams, the construction of some of said seams comprising marginal portions of adjacent sheets raised and lapped, and a Z-shaped member of greater thickness than the sheets extending longitudinally of a seam with its ends riveted to the side plates of the car and with its web portion disposed alongside of one of the side walls of said seam, with its upper flange overlapping and rigidly secured to the top of said seam and with its bottom flange rigidly secured to the body portion of the sheet located adjacent to said side wall of said seam. 110
6. A car roof comprising roof sheets rigidly secured together along their side margins by hollow upstanding seams, the construction of some of said seams comprising marginal portions of adjacent sheets raised and lapped, and a Z-shaped member extending longitudinally of a seam with its web portion disposed alongside of one of the side walls of said seam and parallel to the longitudinal axis thereof, with its upper flange overlapping and rigidly secured to the top of said seam and with its bottom flange rigidly secured to the body portion of the sheet located adjacent to said side wall of said seam, said re- 115
- inforcing member extending from eaves to eaves of the car and rigidly secured thereto. 120
7. A car roof comprising roof sheets extending from side plate to side plate and rigidly secured thereto, said roof sheets being provided along their adjacent margins with seam flanges that are overlapped and rigidly secured together to form seams, and a reinforcing member extending longitudinally of a seam from side plate to side plate and rigidly secured thereto, said reinforcing member being secured to the overlapped seam flanges of adjacent sheets and to the body portion of that sheet which is lowermost at the seam. 125
8. A car roof comprising roof sheets extending from side plate to side plate and rigidly secured thereto, said sheets being provided along their adjacent side margins with seam flanges that cooperate to form hollow upstanding seams, and a Z-shaped reinforcing member located alongside of a seam and extending from side plate to side plate with its ends rigidly secured thereto, said reinforcing member being arranged with its web alongside of but spaced from one side wall of said seam throughout its length, with its upper flange overlapping and rigidly secured to the top of said seam and with its lower flange rigidly secured adjacent to said side wall of said seam to the body portion of that sheet which is lowermost at the seam. 130
9. A car roof comprising roof sheets extending from side plate to side plate and rigidly secured thereto, said sheets being provided along their adjacent side margins with seam flanges that cooperate to form hollow upstanding seams, and a Z-shaped reinforcing member located alongside of a seam and extending from side plate to side plate with its ends rigidly secured thereto, said reinforcing member being arranged with its web alongside of one side wall of said seam, with its upper flange overlapping and rigidly secured to the top of said seam and with its lower flange rigidly secured adjacent to said side wall of said seam to the body portion of that sheet which is lowermost at the seam, said web portion of said reinforcing member being spaced throughout its length from said side wall of said seam. 135
10. A car roof comprising roof sheets extending from side plate to side plate and rigidly secured thereto, said sheets being provided along their adjacent side margins with seam flanges that cooperate to form hollow upstanding seams, and a Z-shaped reinforcing member located alongside of a seam and extending from side plate to side plate with its ends rigidly secured thereto, said reinforcing member being arranged with its web alongside of one side wall of said seam and parallel to the longitudinal axis thereof, with its upper flange overlapping and rigidly secured to the top of said seam by rivets which extend through said sheet flanges and with its lower flange rigidly secured adjacent to said side wall of said seam to the body portion of that sheet which is lowermost at the seam, said web portion of said reinforcing member being spaced throughout its length from said side wall of said seam, said seam and said reinforcing member being of gradually decreased depth from ridge to eaves and said base flange increasing in width from ridge to eaves. 140
